UNITED STATES PATENT OFFICE.

CHARLES M. SANDERS, OF GUTHRIE, OKLAHOMA.

DESIGN FOR A NAPKIN AND TOOTHPICK HOLDER.

53,254.

Specification for Design.

Patented Apr. 29, 1919.

Application filed February 19, 1919. Serial No. 278,080. Term of patent 14 years.

To all whom it may concern:

Be it known that I, CHARLES M. SANDERS, a citizen of the United States, residing at Guthrie, in the county of Logan and State of Oklahoma, have invented a new, original, and ornamental Design for a Napkin and Toothpick Holder, of which the following is a specification, reference being had to the accompanying drawing, forming part thereof.

The figure is a perspective view of a napkin and toothpick holder, showing my new design.

I claim:

The ornamental design for a napkin and toothpick holder as shown.

CHARLES M. SANDERS.
